PERFUMES, COSMETICS, PERFUMED SOAPS,
ESSENCES, AND ANALOGOUS PREPARA-
TIONS

John William Blagden, Ilford, England

No Drawing. Application May 4, 1932, Serial No.
609,336. In Germany May 30, 1931

2 Claims. (Cl. 167—94)

It is known that in the preparation of perfumes, cosmetics, perfumed soaps, essences and the like, the addition of a suitable high-boiling constituent, known as a fixative, has the effect of decreasing the rate of evaporation of the volatile odorous constituents of the preparation, and thus rendering more permanent the odour or taste.

According to this invention, cyclohexyl-cyclohexanol, or a homologue thereof, is incorporated as a fixative in perfumes, perfumed soaps, essences, cosmetics and the like. Cyclohexyl-cyclohexanol may be prepared by condensing cyclohexanone, in the presence of alkali, to produce cyclohexylidene-cyclohexanone and hydrogenating the latter product with hydrogen in the presence of a catalyst. Methylcyclohexyl-methylcyclohexanol can be prepared in an analogous way from methylcyclohexanone.

The fixative action of cyclohexyl-cyclohexanol and its homologues does not depend on the ability of these agents to dissolve the perfume, and is in fact attained with a proportion of the fixative which is insufficient to dissolve the perfume. In carrying out the invention, it suffices to use the fixative in about the proportion in which known fixatives are commonly used, say in a quantity amounting to about 5-15 per cent. of that of the perfume to be fixed.

The following examples illustrate the invention and the improvement attained thereby:—

Example 1.—To lemon oil is added 5 per cent. of its weight of cyclohexyl-cyclohexanol. The product thus obtained is compared with a similar oil containing a known fixative or not containing a fixative, by soaking filter paper or blotting paper with corresponding quantities of the two solutions. On exposure to air, it is found that the perfume remains perceptible on the paper

impregnated with the new mixture long after it has disappeared from that impregnated with the known mixture. Similar results can be obtained in the case of other essential oils, such as bergamot oil or orange oil and in the case of esters, such as amyl acetate and benzyl acetate. Methylcyclohexyl-methylcyclohexanol gives results similar to those obtained with cyclohexyl-cyclohexanol.

Example 2.—A perfume such as eau-de-Cologne is treated with 5-10 per cent. of its weight of one of the fixatives used in accordance with the invention and milled into a toilet soap. After exposure to the air for a month, the soap has a much stronger odour than a sample of the same parent soap containing a known fixative or not containing a fixative and exposed to air for a like period.

Having thus fully described the nature of the said invention and the best means I know for carrying the same into practical effect, I claim:—

1. Perfumed preparations for cosmetic and toilet use, including toilet soaps, which preparations contain a substance adapted to impart odour and as a fixative therefor a material selected from the group consisting of cyclohexyl-cyclohexanol and methylcyclohexyl-methylcyclohexanol.

2. Perfumed preparations for cosmetic and toilet use, including toilet soaps, which preparations contain a substance adapted to impart odour and as a fixative therefor a material selected from the group consisting of cyclohexyl-cyclohexanol and methylcyclohexyl-methylcyclohexanol in proportion not exceeding 15 per cent. of the quantity of the substance adapted to impart odour.

JOHN WILLIAM BLAGDEN.
